UNITED STATES PATENT OFFICE.

GEORGE C. GILLESPIE, OF BROOKLYN, ASSIGNOR TO THE CO-OPERATIVE BUILDING PLAN ASSOCIATION, OF NEW YORK, N. Y.

DESIGN FOR THE EXTERIOR OF A CHAPEL.

SPECIFICATION forming part of Design No. 19,551, dated December 31, 1889.

Application filed December 7, 1889. Serial No. 332,975. Term of patent 8½ years.

To all whom it may concern:

Be it known that I, GEORGE C. GILLESPIE, of Brooklyn, in the county of Kings and State of New York, have invented and produced a 5 new and original Design for the Exterior of a Chapel, of which the following is a specification, reference being had to the accompanying drawings, forming a part thereof.

Figure 1 is a perspective view of a chapel 10 embodying my design. Fig. 2 represents a plan or ground view of the chapel.

Similar letters of reference designate corresponding parts in both the figures.

The general plan of a chapel embodying my 15 design is rectangular on the ground floor, there being at one end a tower.

The front of the chapel embodying my design is illustrated as having a door A, to which a flight of steps a leads. The door A is 20 surmounted by a cornice b and pediment b'. Between the cornice b and the frame of the door A are consoles c. At one side of the door A is a mullioned window B. Beyond the mullioned window B and at the corner of the chapel is a tower C, rising from the ground 25 floor. Between the mullioned window B and the tower C is a doorway D, to which a flight of steps d leads.

The tower C is surmounted by a dome E, upon the top of which is shown a cross e. Between the dome E and the tower C pillars f are represented as extending, a balcony F being between the dome and the upper end of the tower.

The body of the chapel is surmounted by 35 gable roofs G H I. The gable roof G surrounds the front of the chapel, the gable roof H extending to one side thereof and the roof I extending at the rear thereof. Beneath the roof H and at the side of the chapel is a mul- 40 lioned window J.

What I claim is—

The design for the exterior of a chapel, substantially as herein shown and described.

GEORGE C. GILLESPIE.
